LIQUID FLOW PROPORTIONING APPARATUS

Floyd Todd, Springfield, Pa.

Application April 20, 1949, Serial No. 88,580

7 Claims. (Cl. 257—34)

1

This invention relates to liquid flow control apparatus and is particularly adapted to still heads in which it is desired to regulate the reflux ratio between take-off distillate and reflux.

Although there have been prior devices intended to proportion liquid flow and especially devices intended to control the reflux ratio in a still head, such known structures have proved unsatisfactory for a number of reasons. Some devices for this purpose have not been sufficiently accurate to justify the expense of their manufacture. Others have been characterized by relatively complicated and expensive structure which has necessitated extreme care on the part of the operator to obtain satisfactory results. In still others, it has been impossible to obtain a sufficiently wide range of ratios and particularly, in many forms it has been impossible to obtain total collection of distillate if desired.

The present device is extremely accurate, simple to adjust to any desired ratio, and is so constructed that no distillate, or all the distillate, may be taken off as product or returned to the distillation column as reflux.

A primary object of the invention is to provide an extremely simple and inexpensive adjustable means for diverting any desired proportion of a liquid into one or more separate drip paths.

A further object of the invention is to provide a still head assembly in which the total distillate is collected around the lower edge of the condenser neck so that the distillate converges to a single point above the product take-off conduit, and in which a deflector plate enables any desired proportion of the distillate to be returned as reflux before dripping into the reflux collector.

Other objects will be apparent from the specification and drawings in which:

Fig. 1 is a vertical section of a still head having a reflux proportioning device constructed in accordance with the invention;

Fig. 2 is an enlarged fragmentary detail of the reflux ratio adjusting means;

Fig. 3 is a detail in elevation of the ratio proportioning means, shown in Fig. 1, partly sectioned to show the course of the distillate; and

Fig. 4 is a transverse section as seen at 4—4 of Fig. 1.

The invention comprises essentially the provision of a plane, biased annular edge on a liquid conduit providing a plane, operatively continuous surface for the flow of liquid therealong in which the amount of liquid passing through the bore of the conduit enables all of the liquid to flow in relatively close association with said bore so that all of the liquid is collected on the biased edge of the conduit and flows in an uninterrupted continuous path from the higher portions of said edge to the lowest point thereof. The liquid, which in the present embodiment is referred to

2

as distillate, thereupon drips from the lowest point of the plane, biased edge into the funnel-shaped mouth of a take-off conduit. In the present embodiment, the biased annular edge is formed on the bottom of a condenser which is supported in a member known as the still head, which serves as a coupling between the condenser and the distillation column. The biased condenser edge is provided with a plurality of circumferentially spaced, relatively narrow axial slots in which a deflector plate may be positioned and retained by suitable means such as the inherent springiness of the plate. The liquid or distillate running down the plane, operatively continuous biased edge above the deflector flows onto the deflector and drips from the lowermost point of the biased deflector edge to provide a second or reflux drip path which communicates with the distillation column. By selectively positioning the deflector in any opposite pair of slots, the relative amounts of distillate deflected from the condenser tip as distinguished from the deflector tip, may readily be controlled in any desired ratio.

Referring now more particularly to the drawings, the still head assembly designated generally at 10, comprises a reflux condenser 11 utilizing a conventional jacket 12 having coolant passages 13 and 14 in communication therewith, and a passage 15 in communication with the bore 16 of the condenser. Passage 15 may be open to the atmosphere or connected to a suitable source of vacuum, if desired. As the gas or vapor contacts the relatively cool inner walls of chamber 16, it condenses into drops of liquid which flow down the inner walls of the chamber. Condenser 11 is mounted in the tapered neck of head 17 which is provided with a take-off conduit 18, a thermometer well 19, and a tapered ground joint 20 adapted to fit a distillation column (not shown). Conduit 18 extends into the bore of head 17 and is provided with a funnel-shaped mouth 21 which is substantially offset from the center line of condenser 11 and head 17. Conduit 18 may be provided with a suitable stop cock 22, if desired.

The walls 16 of condenser 11 terminate at their lower end in a biased annular edge 23 cut at approximately 45° to provide a plane, operatively continuous surface for the flow of liquid therealong from the highermost to the lowermost point of said edge, and when assembled the lowermost point 23a of edge 23 is positioned above the mouth 21 of conduit 18. Edge 23 is also provided with a plurality of circumferentially spaced, relatively narrow, axial notches or slots 25, 25 which desirably are transversely aligned in pairs. The relative position of slots 25 may be selected in accordance with any predetermined reflux ratio that may be adapted to the particular still head. As stated, slots 25, 25 are circumferentially spaced and are relatively narrow, and hence, are insuffi-

cient in width to interfere with the continuous flow of liquid from the highermost to the lowermost point of edge 23. When, in the present specification and claims, I refer to a plane, operatively continuous edge, I intend to designate an edge substantially devoid of elevations or depressions, one that is substantially even, flat, or forms a part of a single plane. The fact that the open ends of slots 25, 25 open on the edge 23 does not interfere with the continuous flow of the liquid downwardly along said edge. A relatively thin deflector plate 26 is positioned in any pair of slots 25, 25 so that the distillate running down onto any portion of the edge 23 above deflector 26 will run from the edge 23 onto the deflector. Once the liquid is on the deflector, it runs vertically downward thereon and then along the lower biased edge 26a of said deflector to the lowermost point 26b of the deflector edge from which the distillate drops in a path radially displaced from the mouth 21 of conduit 18. It will be understood that deflector 26 may be retained in any pair of slots by the thickness of the plate with respect to the slots, but I have found that the provision of a somewhat resilient plate, preferably of metal, which is bent into a V shape (as shown in Fig. 2) provides ample pressure to hold the deflector in the slots.

Fig. 3 illustrates how drops or streams of distillate running down the inner walls of chamber 16 below the position of deflector 26 will eventually strike edge 23 at some point below the slots in which the deflector is held, whereupon the liquid follows the plane, operatively continuous edge down to tip 23a to drip into conduit 18. Likewise, as explained previously, all distillate running from the condenser which strikes edge 23 above deflector plate 26, will be directed away from conduit 18 and through joint 20. As shown in Fig. 3, the width of slots 25 is such that the flow of liquid either in droplets or in a stream along edge 23, is operatively continuous and will not be entirely interrupted by the relatively narrow slots so that there will be more than one drip point. It will be understood that the number of ratio adjustments is limited only by the number of slots 25 which may be provided in edge 23 so that an extremely wide range may be achieved. When funnel 21 is substantially offset, as shown in Fig. 1, it is entirely feasible to rotate condenser 11 so that no distillate whatsoever will be received by conduit 18. It is not necessary that the deflector be positioned in opposite registering slots if an immediate ratio is desired because the thickness of the deflector with respect to the slots is such that it may be moved one slot at a time on either side.

While the liquid portioning or control device described herein is illustrated in conjunction with a still head, it will be understood that the same structure is applicable for any purpose in which there is a liquid flow around the inner periphery of a hollow member and it may be desired to divert a portion of such flow into one or more separate channels or paths.

Having thus described my invention, I claim:

1. In a still head apparatus for selectively obtaining a reflux ratio, a hollow liquid conduit adapted to carry liquid downwardly along the periphery of the bore of said conduit, a single biased discharge edge forming the bottom of said conduit, said edge being plane and receiving all of the liquid flowing through the bore of said con-

duit and providing an operatively continuous surface for the flow of said liquid therealong from the highermost to the lowermost point of said edge, said lowermost point providing a first drip path for the liquid, and a deflector in operative association with said biased edge for interrupting the flow of liquid therealong from the highermost to the lowermost point of said edge for deflecting a portion of the liquid flowing along said edge away from said lowermost point, said deflector providing a second drip path for the liquid separate from the first drip path.

2. A still head apparatus for selectively obtaining a reflux ratio as defined in claim 1, in which said deflector has a biased lower edge providing an operatively continuous surface for the flow of liquid therealong for the highermost to the lowermost point of said edge, said lowermost point of said biased lower edge of said deflector providing said second drip path.

3. A still head apparatus for selectively obtaining a reflux ratio as defined in claim 1 in which said deflector is adjustable along the biased edge of said conduit to vary its position with respect to said lowermost point of said biased edge of said conduit, and wherein means are provided adjacent said biased edge of said conduit for maintaining said deflector in its adjusted position.

4. A still head apparatus for selectively obtaining a reflux ratio as defined in claim 1 in which the biased lower edge of said conduit is provided with relatively narrow circumferentially spaced slots at varying distances from the lowermost point of said edge, and wherein said deflector is adapted for selective positioning within at least one of said slots, said deflector being retained in the selected one or more slots by engagement between said deflector with a wall defining said one or more slots.

5. A still head apparatus for selectively obtaining a reflux ratio as defined in claim 1 in which the biased lower edge of said conduit is provided with circumferential spaced pairs of relatively narrow slots, one slot of each pair being positioned at opposite sides of the lowermost point of said edge, and the pairs of slots being at varying distances from said lowermost point of said edge, said deflector being positioned within a selected pair of said slots and being frictionally retained therein.

6. A still head apparatus for selectively obtaining a reflux ratio as defined in claim 5, in which the deflector comprises an axially bendable, resilient plate.

7. A still head apparatus for selectively obtaining a reflux ratio as defined in claim 6 in which said deflector has a biased lower edge and in which the lowermost point of said edge provides said second drip path.
